US00D950533S

(12) **United States Design Patent** (10) **Patent No.:** **US D950,533 S**
Jia (45) **Date of Patent:** **** May 3, 2022**

(54) **DISPLAY MOUNT**

(71) Applicant: **SHENZHEN BESTQI INNOVATION TECHNOLOGY CO., LTD**, Shenzhen (CN)

(72) Inventor: **Daqiang Jia**, Shenzhen (CN)

(73) Assignee: **SHENZHEN BESTQI INNOVATION TECHNOLOGY CO., LTD**, Shenzhen (CN)

(**) Term: **15 Years**

(21) Appl. No.: **29/756,186**

(22) Filed: **Oct. 27, 2020**

(51) **LOC (13) Cl.** **14-03**

(52) **U.S. Cl.**

USPC **D14/239**

(58) **Field of Classification Search**

USPC D14/239, 371, 372, 373, 374, 375, 376, D14/377, 447-450, 451, 452, 335-337, D14/125, 127, 128, 129, 341; D8/355, D8/363, 373; D6/672, 682

(Continued)

Primary Examiner — Lauren D McVey

(57) **CLAIM**

The ornamental design for a display mount, as shown and described.

DESCRIPTION

FIG. 1 is a perspective view of a display mount showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines immediately adjacent to the shaded areas depict the bounds of the claimed design, while all other broken lines are directed to environment. The broken lines form no part of the claimed design.

1 Claim, 8 Drawing Sheets
